ASSIGNORS TO HARRIS-SEYBOLD-POTTER COMPANY, OF CLEVELAND, OHIO, A COR-
PORATION OF DELAWARE

PLATE-CLAMP

Application filed September 22, 1928. Serial No. 307,583.

Our invention relates to improved clamping mechanism for securing flexible sheets or plates in even and firm contact with a suitable support, such as a printing-press cylinder, and is particularly adapted for securing the zinc plates to the cylinders in offset printing presses, though it may be advantageously used in other types of presses.

The objects of our invention are, among other things, to provide a simple and novel clamp mechanism for such printing plates which shall be convenient to operate and which shall strain and hold the plate wrapped about the cylinder surface with a uniform tension in all directions so as to prevent any wrinkles or unevenness on the surface of the flexible plate whereby accurate printing is ensured; also to provide a simplified device to facilitate the shifting of the flexible printing plate for properly positioning same and also to enable the plate to be readily shifted in all directions without actually releasing same so as to produce accurate adjustments.

A further object of our invention is to provide a plate-clamping mechanism of such a character that a small opening or gap in the cylinder will afford sufficient space for its location and manipulation while permitting an almost continuous printing surface on the cylinder while diminishing the width of the gap when the plate is in stretched printing position.

A further feature of our invention is the provision of an improved plate-clamp embodying the desired attributes of simplicity, efficiency and durability, and which will enable the flexible plate not only to be clamped to the cylinders and easily and quickly loosened therefrom, but also to be readily shifted or positioned transversely, longitudinally and angularly on its supporting member with a reduction of the likelihood of derangement or mutilation of the plates to a minimum in such operations in that the adjusting mechanism is conveniently located outside the zone of such printing plates wrapped about the cylinders.

With these and other objects in view, our invention comprises the construction, combination and arrangement of the various

parts hereinafter described, and then particularly pointed out in the appended claims.

In the accompanying drawings, Fig. 1 is a front elevation of the cylinder and flexible plate wrapped about the cylinder which is partly broken away to show our improved plate-clamp in a preferred form;

Fig. 2 is a longitudinal section taken on the line 2—2 of Fig. 1;

Fig. 3 is an enlarged transverse section 60 taken on the line 3—3 of Fig. 1;

Fig. 4 is an enlarged end view of part of the cylinder and associated parts shown in Figs. 1 and 2;

Figs. 5, 6 and 7 are detailed perspective 65 views of some of the clamping members shown in Figs. 1, 2 and 3;

Fig. 8 is a view like Fig. 1 showing a modified form of the plate-clamping mechanism;

Fig. 9 is an enlarged transverse section 70 taken on the line 9—9 of Fig. 8;

Fig. 10 is a fragmentary section of another modified form; and

Fig. 11 is a fragmentary end view partly in section showing a third modified form of our 75 plate-clamping mechanism.

Similar numerals refer to similar parts throughout the several figures.

Referring more particularly to Figs. 1-7, the press cylinder 12 is of the customary hollow construction having the peripheral cylindrical side-walls 13 integral with the ends 14 each of which ends is provided with the outwardly extending bosses 15 which serve to support the cylinder 12 in the press framework bearings (not shown). Extending longitudinally along the surface of the cylinder 12 is the T-shaped slot 16 (Fig. 3) having the inwardly extending side flanges 17, within which slot the plate-clamping mechanism is located. Fastened to the cylinder 12 by bolts 18 in the wider portion of the slot 16 are two oppositely-disposed longitudinal guide-members 19, the outer surfaces of which are co-extensive with the peripheral 85 surface of the cylinder 12 as shown in Fig. 3. Each guide-member 19 is provided with a flaring groove 20 (Fig. 5) within which slide the cam-plates 21 (Fig. 6) having the longitudinal grooves 22 within which the slid- 90 able 95

cam-bars 23 (Fig. 7) are located (Fig. 3). The plates 21 have the spaced-apart pins 24 riveted thereto and extending through the grooves 22, and these pins 24 are adapted to be engaged by the equally spaced-apart angular cam faces 25 integral with the cam-bars 23 as shown in Figs. 1 and 7. Each cam-plate 21 has the rounded upwardly-projecting nose 26 opposite the groove 22 and adjacent the opening of the grooves 20 (Fig. 3), around which noses 26 the cylinder plate P is drawn when fastened to the cylinder 12.

Within the inner portion of the slot 16 and adjacent the flanges 17 (Fig. 3) are arranged two oppositely-disposed plates 27 which are adapted to slide radially within the slot 16 and in contact with the flanges 17. The plates 27 are slightly longer than the cylinder 12 (Fig. 2), and have reduced end portions 28 which project through openings in the cylinder ends 14. The plates 27 are also provided with oppositely-disposed longitudinal guide grooves 29 in which slide the clamping bars 30. Each of the reduced ends 28 carries a downwardly projecting pin 31 around which is the coiled spring 32 which bears on the bottom edge of the openings 33 formed in the cylinder ends 14 and also bears on the reduced ends 28 as shown in Figs. 2 and 4.

Projecting outwardly from, and fastened to, the cylinder ends 14 are the brackets 34 which partially enclose the ends 28 of the plates 27 (Fig. 2), and each of these brackets 34 carries a pair of screw-threaded bolts 35 the tips of which bear on the vertical surfaces of the reduced ends 28 for end adjustment of the plates 27, while a pair of vertically-disposed screw-bolts 36 passing through the brackets 34 coat with the top surfaces of the plate ends 28 for radial adjustment of the plates 27. Such bolts 35 and 36 being located outside the cylinder ends 14 afford convenient manipulating means for making both end and radial adjustments for the plates 27.

The cylinder ends 14 also carry the rings 37 which are coincident with the peripheral surface of the cylinder 12 when provided with the plate P (Figs. 1 and 2), and each of these rings 37 is provided with a pair of horizontally-disposed screw-bolts 38 which bear on opposite ends of the cam-bars 23 to adjust the latter longitudinally of the cylinder 12. The ends of the plate P are held to the clamping bars 30 by the clamping members 39 fastened to the bars 30 by the set-screws 40 as shown in Figs. 2 and 3.

When the plate P is wrapped loosely in position about the cylinder 12 and is held in place by the clamping mechanism just described in the preceding paragraph, such clamping-bars 30 may be adjusted to shift the plate P longitudinally on the cylinder 12 by operating the screw-bolts 35. After the plate P has been properly adjusted longitudinally it may then be stretched tight about the

cylinder 12 by operating the screw-bolts 36 which acts to push the plates 27 radially toward the axis of the cylinder 12 thereby carrying the two ends of the plate P with such plates 27 (Fig. 3), and compressing the springs 32 (Fig. 4). Further tightening of the plate may be attained by operating the screw-bolts 38 which slide the cam-plates 21 toward each other thereby straining the plate P and partially closing the gap between the ends of the plate as shown by dotted lines in Fig. 3, whereby the plate-supporting surface of the cylinder 12 is advantageously increased. The coil springs 32 bearing on the ends 28 of the plates 27 will keep the latter in a loose position when the screw-bolts 36 are loosened in the brackets 34.

Referring to the modified form of our improved plate-clamping mechanism shown in Figs. 8 and 9, a pair of oppositely-disposed complementary cam-bars 41 and 42 are arranged with their angular faces abutting (Fig. 8), and slide in the wide end of the T-shaped slot 16 to form expanding or contracting wedge members therein as they are adjusted by pairs of horizontally-disposed screw-bolts 43 passing through the two rings 37 fastened to the cylinder ends 14. The two adjacent inside cam-bars 41 carry hardened steel rounded noses 45 over which the ends 25 of the plate P are bent and travel (Fig. 9).

By operating the pairs of screw-bolts 43 the cam-bars 41 and 42 will tend to draw the plate P tighter on the cylinder 12 and also diminish the width of the gap between the bar-noses 45 as the cam-bars 41 and 42 are shifted on each other in opposite directions. A reverse movement of the cam-bars 41 and 42 will relax the tension on the plate P and so loosen same on the cylinder 12.

Fig. 10 shows another modified form of mechanism for clamping and stretching the cylinder plate P about the cylinder 12. In the upper wide portion of the T-slot 16 cut in the cylinder 12 are placed two oppositely-disposed guide members 46 fastened to the cylinder 12 by screws 47. These members 46 have irregular inner sloping surfaces 48 which receive irregular shaped clamping bars 49 to which are fastened the ends of the cylinder 115 plate P by clamping means 50. The clamping-bars 49 also have threaded apertures 51 which carry screw-bolts 52. Said screw-bolts 52 have their oppositely-disposed heads in contact with each other and the opposite ends of the screw-bolts 52 contact with the inner vertical walls of the guide members 46. It can be readily understood that upon turning the screw-bolts 52 in certain directions motion is given to the clamping-bars 49 which results in either tightening or loosening the cylinder plate P around the cylinder 12.

Fig. 11 shows a third modified form of construction similar to the preferred form with the exception that the lower end of the T-slot 130

16 in the cylinder casting is one-half as wide as in Fig. 3. The means for clamping and adjusting right end of the cylinder plate P is the same as in Fig. 3, but the other left end 5 of the cylinder plate P with its clamping means 53 fits in an irregular slot or groove 54 cut in a shaft 55 which has bearings in the end portions 14 of the cylinder 12. At the near end (in Fig. 11) the shaft 55 is 10 squared to receive a wrench or crank by which it may be rotated, thereby drawing that end of the cylinder plate P tighter on the cylinder 12. Also mounted on one end of the shaft 55 is a ratchet 56 coacting with a pawl 57 held 15 in position by a flat spring 58. The pawl 57 is so designed with a flat surface 59 along its back that it may be swung out of engagement with ratchet 56 and held out of such engagement by the spring 58 bearing on the flat surface 59.

In all the forms shown and described we have provided means for increasing or diminishing the width of the slot 16 coincident with the printing surface of the plate P without 25 the necessity of changing the adjustment of the clamping members which hold the ends of such plate. When the plate P is tensioned the supporting area on the cylinder 12 beneath the plate is thereby increased. Our invention 30 is not to be restricted to the precise details of construction shown since various changes and modifications may be made therein without departing from the scope of the invention or sacrificing the advantages derived from its use.

We claim as our invention:

1. A plate-clamp for positioning a flexible plate on its support comprising clamping members to grip the plate ends, complementary cam members bearing on the plate adjacent the plate ends, and means to slide said cam members on each other in both directions without moving said clamping members to tension and loosen said plate on said support.
2. A printing cylinder having a gap, clamping members within the gap to grip the ends of a flexible plate wrapped about the cylinder, complementary cam members bearing on the plate adjacent the plate ends to 50 tension the plate on said cylinder, and means to slide said cam members on each other in both directions without moving said clamping members to tension and loosen said plate on said cylinder.
3. In combination, a printing cylinder having a gap, means for holding a flexible plate thereto, a grooved plate bearing on the flexible plate adjacent its end, a coacting cam bar extending longitudinally within the grooved plate and adjusting screws coacting with the ends of said bar to shift said grooved plate for drawing the flexible plate tight on said cylinder without moving said plate holding means.
4. In combination, a printing cylinder hav-

ing a gap, means for holding a flexible plate thereto, a grooved plate bearing on the flexible plate adjacent its end, a coacting cam bar extending longitudinally within the grooved plate and adjusting screws located outside the cylinder ends and coacting with the ends of said bar to shift said grooved plate for drawing the flexible plate tight on said cylinder without moving said plate holding means.

5. A printing cylinder having a gap, clamping bars within the gap to grip the ends of a flexible plate wrapped about the cylinder, complementary cam-bars coacting with said plates, and oppositely-disposed coacting threaded members associated with said cam bars for moving the latter edgewise in mutual parallelism without moving said clamping bars.

6. A printing cylinder having a gap, clamping means within the gap to hold the end of a flexible plate on the cylinder, said means being movable angularly, longitudinally and transversely with respect to said cylinder, and means for changing the width of said cylinder gap without moving said clamping means or altering the adjustment thereof.

7. A printing cylinder having a gap, clamping means within the gap to hold the end of a flexible plate on the cylinder, said means being movable angularly, longitudinally and transversely with respect to said cylinder, and means bearing on said plate adjacent the plate ends for changing the width of said cylinder gap without moving said clamping means or altering the adjustment thereof.

8. A printing cylinder having a gap, clamping means within the gap to hold the end of a flexible plate on the cylinder, said means being movable angularly, longitudinally and transversely with respect to said cylinder, and means for tensioning the plate independently of said clamping means without moving same.

9. A printing cylinder having a gap, means within the gap for holding the ends of a flexible plate wrapped about the cylinder, and other means within the cylinder bearing on the plate adjacent its ends with a gradually increasing pressure to increase the plate-supporting area of the cylinder beneath the plate adjacent the gap without changing the bend in the plate or moving said plate-holding means.

10. A printing cylinder having a gap, means within the gap for holding the ends of a flexible plate wrapped about the cylinder, and other means within the cylinder bearing on the plate adjacent its ends with a gradually increasing pressure to increase the plate-supporting area of the cylinder beneath the plate adjacent the gap and also tighten the latter on the cylinder without changing

the bend in the plate or moving said plate-holding means.

11. A printing cylinder having a gap, means within the gap for holding the ends of a flexible plate wrapped about the cylinder, means for shifting said holding means to register the plate on the cylinder, and other means within the cylinder bearing on the plate adjacent its ends with a gradually increasing pressure to increase the plate-supporting area of the cylinder beneath the plate adjacent the gap without changing the bend in the plate or moving said plate-holding means.

12. A plate-clamp for positioning a flexible plate on its support comprising means for holding the plate ends in position and positively-actuated means bearing along the supported line of the plate between said support and holding means to increase the supported area of the plate while drawing same tight on said support without changing the bend in, or moving said holding means secured to, said plate ends.

13. A printing cylinder having a gap, clamping bars within the gap to grip the ends of a flexible plate wrapped about the cylinder, complementary cam-bars having projecting noses bearing on the plate adjacent the plate ends, and oppositely-disposed, coacting threaded members associated with said cam-bars for moving the latter edgewise in mutual parallelism without moving said clamping bars.

14. A plate-clamp for positioning a flexible plate on its support comprising clamping members to grip the plate ends, positively-actuated expansible cam members having projecting noses bearing on the plate adjacent the plate ends while drawing same tight to increase the supported area of the plate on said support without moving said clamping members secured to said plate.

15. A printing cylinder having a gap, clamping members within the gap to grip the ends of a flexible plate wrapped about the cylinder, and positively-actuated expansible cam members having projecting noses bearing on the plate adjacent the plate ends while drawing same tight to increase the supported area of the plate on said cylinder without moving said clamping members.
